UNITED STATES PATENT OFFICE.

JAMES T. MORSE, OF RIPPEY, IOWA.

CHURN.

SPECIFICATION forming part of Letters Patent No. 625,119, dated May 16, 1899.

Application filed March 1, 1899. Serial No. 707,269. (No model.)

To all whom it may concern:

Be it known that I, JAMES T. MORSE, a citizen of the United States, residing at Rippey, in the county of Greene and State of Iowa, have invented a new and useful Churn, of which the following is a specification.

The invention relates to improvements in churns.

The object of the present invention is to improve the construction of churns, to increase their efficiency, and to provide a simple and comparatively inexpensive one which will be strong and durable and which will enable the dasher and the churn-body to be readily removed from the supporting-frame and separated.

The invention consists in the construction and novel combination and arrangement of parts hereinafter fully described, illustrated in the accompanying drawings, and pointed out in the claims hereto appended.

In the drawings, Figure 1 is a perspective view of a churn constructed in accordance with this invention. Fig. 2 is a similar view, the churn-body being removed. Fig. 3 is a plan view, partly in section. Fig. 4 is a transverse sectional view taken longitudinally of the horizontal shaft, the parts being arranged as shown in Fig. 1.

Like numerals of reference designate corresponding parts in all the figures of the drawings.

1 and 2 designate vertical standards of a supporting-frame, provided at their lower ends with divergent legs 3 and connected at the tops thereof by a bottom cross-bar 4, upon which is mounted a horizontal base 5, preferably constructed of wood and forming a support for a churn-body 6. The upper ends of the standards 1 and 2 are connected by a top cross-bar 7, provided at its terminals with depending portions 8, secured by suitable fastening devices to the standards, on the exterior thereof, as clearly illustrated in Figs. 2 and 4 of the accompanying drawings. The cross-bar 7 is provided at its center with a horizontally-curved portion 9 to provide a space for the gearing, hereinafter described, and one of its ends is provided with an upwardly-ex-

tending arm 10, located above the standard 2 and having one end of a vertical frame or guard 11 secured to it. The vertical frame or guard 11, which has its lower end secured to the exterior of the standard 2, is provided at its terminals with angular bends, as shown, and it forms a space for a balance-wheel 12 and assists in supporting the same.

The curved portion 9 is offset from the end portions of the top cross-bar 7, and the recess or space is arched by a top bearing 13, composed of sections 14 and 15 and provided with a central bearing-opening for the reception of a vertical dasher-shaft 16. The section 14 of the top bearing is rigidly secured to the adjacent portion of the bar 7 by a bolt 17 or other suitable fastening device, and its inner portion is curved upward and matches a similarly-curved inner portion of the section 15, which is provided with a slot 18, through which passes a thumb-screw 19 for securing the movable section 15 to the supporting-frame. The thumb-screw is adapted to be loosened to permit the movable section 15 to be drawn outward and swung aside, so that the dasher-shaft may be readily detached from its upper bearing. The top cross-bar is provided at its upper face with shoulders or lugs 20, located at the terminals of its central curved portion 9 and having the adjacent portions of the sections 14 and 15 of the bearing 13 abutting against them, whereby the fastening devices 17 and 19 are adapted to secure the said sections 14 and 15 rigidly to the supporting-frame.

The dasher-shaft, which is stepped in a suitable bearing or socket 21 of the churn-body, carries near its upper end a bevel-pinion 22, keyed or otherwise secured to the shaft and meshing with a vertical bevel gear-wheel 23, which is mounted on the inner end of a horizontal shaft 24, extending from the center of the supporting-frame to the standard 2. The shaft 24 is journaled in a bearing formed by enlarging and grooving the side portion 25 of the bar 7 and by a detachable bar or plate 26, which is secured to the enlarged portion of the bar 7 and which has a corresponding groove or channel. The bolt 17 engages a

threaded opening of the top cross-bar, and the bar or section 26 is detachably secured to the same by bolts or any other suitable fastening devices.

5 The outer end of the horizontal shaft 24 carries a spur-pinion 27, which meshes with spur-teeth 28 of the balance-wheel 12, which is mounted in the space within the vertical frame or guard. The gear 28 is formed integral with 10 the balance-wheel 12, and the shaft thereof is journaled in suitable bearings of the standard 2 and the guard or frame 11 and has a crank 29 fixed to it. The main balance-wheel 15 is disposed in a vertical plane, and the dasher-shaft 16, which extends above the curved center of the top bearing 13, carries a horizontal balance-wheel 30, located above the supporting-frame and suitably keyed to the shaft 16.

The churn-body, which is in the form of a 20 truncated cone, tapers toward its top and is preferably constructed of sheet metal, being provided at its upper edge with a metal ring 31, having sockets for the reception of the inner ends of horizontal thumb-screws 32, 25 mounted in threaded perforations of the standards 1 and 2 and detachably securing the churn-body upon the base 5. The churn-body is provided with a sectional cover having a depending flange 33 at its periphery to fit 30 within the body and provided at the adjacent inner edges of the sections with depending flanges 34, forming abutting faces.

The dasher-shaft carries a spiral or auger-shaped dasher 35, adapted when rotated in 35 one direction to throw the cream upward and outward and produce a continuous agitation of the same, and after butter has been produced the dasher may be rotated in the opposite direction to collect the same.

40 The invention has the following advantages: The churn, which is simple and comparatively inexpensive in construction, possesses great strength and durability. It is easily operated and it is capable of rapidly producing butter. 45 The movable section of the upper bearing enables the dasher-shaft to be readily disconnected from the supporting-frame, and the thumb-screws enable the churn-body to be readily removed and replaced, only one of the 50 screws being loosened to free the said body.

Changes in the form, proportion, size, and the minor details of construction within the scope of the appended claims may be resorted to without departing from the spirit or sacrificing any of the advantages of this invention. 55

What is claimed is—

1. In a device of the class described, the combination of a supporting-frame comprising standards, a top cross-bar connecting the 60 standards and provided with a central offset portion, and a base connecting the lower portions of the standards, a sectional bearing mounted on the top cross-bar and arched over the central offset portion thereof, one of its 65 sections being movable, a dasher-shaft de-

tachably journaled in the sectional bearing, and gearing for operating the dasher-shaft, substantially as described.

2. In a device of the class described, the combination of a supporting-frame provided 70 at its top with an offset portion arranged at the center, an arched sectional bearing mounted on the top of the supporting-frame at the center thereof, one of the sections being movable, the detachable bearing plate or bar arranged beneath the top of the supporting-frame and disposed horizontally, a horizontal shaft journaled between the plate or bar and the top of the frame, a vertical dasher-shaft journaled in the sectional bearing, gearing arranged at the inner end of the horizontal shaft and connecting the same with the dasher-shaft, and gearing located at the outer end of the horizontal shaft for operating the same, substantially as described. 75

3. In a device of the class described, the combination of vertical standards, a top cross-bar having a central offset portion and provided with depending portions located at its ends and connected to the said standards, 80 one end of the cross-bar being provided with an upwardly-extending arm, a vertical guide or frame secured to the said arm and to the adjacent standard and offset from the latter, an arched sectional bearing mounted upon 85 the cross-bar, one of the sections being movable, a vertical dasher-shaft journaled in the sectional bearing, a horizontal shaft journaled on the cross-bar and extending from the central portion thereof to the vertical guard or 90 frame, inner gearing connecting the inner end of the horizontal shaft with the dasher-shaft, and outer gearing arranged within the 95 vertical guard or frame and connected with the outer end of the horizontal shaft, substantially as described.

4. In a device of the class described, the combination of vertical standards, a cross-bar connecting the standards and having a central offset portion, the top bearing 13 arched 100 over the offset portion and composed of sections 14 and 15, one of the sections being slotted, fastening devices 17 and 19 securing the sections to the cross-bar, the fastening device 19 being arranged in the said slot, a lower 105 bearing-plate detachably secured to the lower face of the cross-bar, a horizontal shaft journaled between the lower bearing-plate and the cross-bar, a vertical dasher-shaft provided with a dasher, gearing connecting the 110 said shafts, and means for operating the horizontal shaft, substantially as described.

5. A device of the class described comprising a supporting-frame having an offset top portion, a sectional bearing arched over the 115 same, a vertical dasher-shaft detachably journaled in the sectional bearing and carrying a dasher, a horizontal balance-wheel located above the supporting-frame and mounted on the dasher-shaft, a horizontal shaft journaled 120

on the supporting-frame and having its inner end connected by gearing with the dasher-shaft, a vertical guard mounted on the supporting-frame at the outer end of the horizontal shaft, and a vertical balance-wheel arranged within the guard and connected by gearing with the outer end of the horizontal shaft, substantially as described.

In testimony that I claim the foregoing as my own I have hereto affixed my signature in the presence of two witnesses.

JAMES T. MORSE.
